NECKLACE OR THE LIKE

Adolph Katz, Providence, R. I., assignor to Coro, Inc.,
New York, N. Y., a corporation of New York

Application January 16, 1956, Serial No. 39,788

Term of patent 7 years

(Cl. D45—16)

Fig. 1

Fig. 1 is a plan view of a necklace or the like showing my new design.

Fig. 2 is an edge view of the pendant portion.

The dominant feature of new design resides in the portions shown in solid lines.

I claim:

The ornamental design for a necklace or the like, substantially as shown and described.
